UNITED STATES PATENT OFFICE

CHARLES T. LA MONT, OF MILWAUKEE, WISCONSIN

STOCKING MARKER

Application filed June 25, 1928. Serial No. 288,128.

This invention relates to stocking markers.

This invention is an improvement over that disclosed in my prior Patent No. 1,660,077 of February 2, 1928, for stocking markers, and in my copending application Serial No. 175,397, filed March 14, 1927, for stocking markers.

Objects of this invention are to provide a novel form of stocking marker which is so constructed that it may be run across a stocking to separate the stitches to the desired extent, thus facilitating placing a partially knit stocking upon the needles of a machine as, for example, when the stocking is transferred from one machine to another during the process of knitting it.

Further objects are to provide a marker which is so constructed that means are provided for drawing it inwardly while at the same time permitting the utmost freedom of manipulation on the part of the operator for guiding the marker across a stocking.

Further objects are to provide a device which is of extremely simple construction and which may be easily made by ordinary machine shop processes and which has a very small number of parts.

An embodiment of the invention is shown in the accompanying drawings in which:

Figure 1 is a side view with parts in section showing the marker in one position;

Figure 2 is a plan view of the structure shown in Figure 1 with parts broken away.

Referring to the drawings, it will be seen that the device comprises a base plate 1 which may be formed of wood or other suitable material and which has tacked or otherwise secured thereon a yielding top face plate 2, which may be of leather, composition, or other material, preferably yielding, as this characteristic facilitates the operation of the device.

The base plate carries a spring receiving body portion 3 which is provided with a cylindrical concavity 4, the concavity being closed by means of a face plate 5 held in place by means of a bolt 6. This bolt is slotted as indicated at 7 to receive the transversely bent end of a spiral spring 8. The other end of the spring passes freely through a slot 9

formed in the casing 3 and its outer end is looped and carries an eyelet 10.

Further, the casing 3 is provided with a bearing face 10 upon which a guide 11 is carried. This bearing face 10 is provided with an upwardly extending ear 12 against which the guide 11 may contact.

The ear 12 is positioned to one side of the bearing plate 10 as is apparent from Figure 1. The guide 11 is provided with an elongated slot 13 through which a headed pin 14 passes. The lower head of the pin is received in an offset portion of the casing 3, as is apparent from Figure 1. The pin 14 is provided with an upper washer and with a spring 15 which bears lightly against a lower washer in contact with the slide 11. This yieldingly holds the slide in contact with the bearing face 10, and the pin and the lip or ear 12 cooperates to prevent too great a side swinging of the slide 11. The outer end of the slide 11 is provided with an aperture 16.

The marker consists of a pointed plunger 17 whose lower end is conical and terminates in a rounded tip 18. The upper end of the plunger is provided with a head 19. The plunger is guided by means of a bushing 20 forced into the interior cavity of the body portion 21. The body portion 21 carries a spring 22 which forces the plunger outwardly. A threaded cap 22' is screwed on a reduced projecting portion of the body 21, as shown in Figure 1, and clamps the lower eyelet of a connecting link or wire 23 in place upon the body portion. Preferably, the body portion is provided with a rubber covering 24 which bulges outwardly to form a knob at its upper end. Obviously, other materials, such as bakelite, for instance, could be substituted for the rubber.

The link 23 is provided with an eyelet 25 at its upper end which fits through the opening 16 in the guide 11 through the eyelet 10 carried by the outer end of the spring 8.

In using the device, the stocking is laid upon the yielding table or plate 2 and the marker is moved across the stocking, the spring aiding in drawing the marker forwardly.

Further, it will be seen that the marker is

held in a position convenient for grasping by the operator so that it is always in approximately its correct position upon the work table.

5 The housing 3, it is to be particularly noted, is provided with a pointed or tapered end 26 in line with the normal innermost position of the marker. The purpose of this is to guide the point of the marker laterally so that it will not strike against a flat surface and consequently will not become flattened or worn. Instead, the marking point is deflected and the marker swung at a slight transverse angle so that wearing of the point 15 does not occur.

It will be seen further that the device relieves the operator of a considerable amount of effort, as the spring draws the marker forwardly during the marking operation.

20 Although the invention has been described in considerable detail, such description is intended as illustrative rather than limiting as the invention may be variously embodied and as the scope of such invention is to be 25 determined as claimed.

I claim:

1. A stocking marker comprising a base portion, a yielding bearing plate secured to the upper side of said base portion and upon 30 which a stocking is adapted to be laid, a housing having a concavity therein, a spiral spring carried within said concavity and having an end portion locked with respect to said housing, said housing having a slot 35 and said spring having its outer end projecting through said slot, said housing having a substantially horizontal bearing face, a guide having one face slidably engaged with said bearing face, means for yieldingly 40 urging said slide in contact with said bearing face, a marker positioned beyond the outer end of said guide, and a link connecting said marker and said guide.

2. A stocking marker comprising a base 45 portion, a yielding bearing plate secured to the upper side of said base portion and upon which a stocking is adapted to be laid, a housing having a concavity therein, a spiral spring carried within said concavity and 50 having its portion locked with respect to said housing, said housing having a slot and said spring having its outer end projecting through said slot, said housing having a substantially horizontal bearing face on the top 55 thereof, a slide having one space slidably engaged with said bearing face, means for yieldingly urging said slide into contact with said bearing face, a marker positioned beyond the outer end of said slide, and a link 60 connecting said marker and said slide, said slide having an elongated slot therein, and said casing having a pin passing through said slot.

3. A stocking marker comprising a base 65 portion, a yielding bearing plate secured to

the upper side of said base portion and upon which a stocking is adapted to be laid, a housing having a concavity therein, a spiral spring within said concavity having one end portion locked with respect to the housing, 70 said housing having a slot with the other end of the spring projecting through the slot, said housing having a horizontally disposed bearing face on the top thereof, a slide slidably mounted upon said bearing face, means for connecting the outer end of the spring with the outer end of the slide, means for yieldingly urging said slide into contact with the bearing face, a marker positioned beyond the outer end of said slide and a link connecting 75 said marker and slide, the slide having an elongated slot therein and a casing having a pin carried by the top thereof passing through the slot.

In testimony that I claim the foregoing I have hereunto set my hand at Milwaukee, in the county of Milwaukee and State of Wisconsin.

CHARLES T. LA MONT.
